(57) **CLAIM**

The ornamental design for a digital camera, as shown and described.

DESCRIPTION

FIG. 1 is a perspective view of the top, front and right side of a digital camera showing our new design;

FIG. 2 is a perspective view of the top, rear and left side thereof;

FIG. 3 is a top plan view thereof;

FIG. 4 is a front elevational view thereof;

FIG. 5 is a left side elevational view thereof;

FIG. 6 is a right side elevational view thereof;

FIG. 7 is a rear elevational view thereof;

FIG. 8 is a bottom plan view thereof; and,

FIG. 9 is a right side elevational view thereof showing the lens in an extended position.

The portions shown in broken lines are for illustrative purposes only and form no part of the claimed design.
